UNITED STATES PATENT OFFICE.

JAMES HENDERSON AND HARRY G. PEAKE, OF OROVILLE, CALIFORNIA.

DREDGE.

SPECIFICATION forming part of Letters Patent No. 779,782, dated January 10, 1905.

Application filed October 5, 1904. Serial No. 227,234.

To all whom it may concern:

Be it known that we, JAMES HENDERSON and HARRY G. PEAKE, both citizens of the United States, and residents of Oroville, in the county 5 of Butte and State of California, have invented a new and Improved Dredge, of which the following is a full, clear, and exact description.

Our invention relates to dredges adapted for the raising of gold-bearing sands and similar operations. Its principal objects are to provide a durable structure the movable parts 10 of which are in positive engagement.

Reference is to be had to the accompanying drawings, forming a part of this specification, 15 in which similar characters of reference indicate corresponding parts in all the figures.

Figure 1 is a side elevation of a dredge to which one embodiment of our invention is applied. Fig. 2 is a longitudinal sectional detail through the lower end of the frame on the line 2 2 of Fig. 3. Fig. 3 shows in elevation the lower supporting-wheel. Fig. 4 is a 20 side elevation of the upper wheel, parts being broken away and parts in section on the line 4 4 of Fig. 5. Fig. 5 is an edge elevation thereof. Fig. 6 is a detail in plan of one 25 of the wearing-plates, and Fig. 7 is a transverse sectional detail through the lower end of the frame and particularly illustrating the 30 shield.

10 designates a floating structure, upon which is mounted a frame 11, conveniently pivoted about a shaft 12, rotatable in suitable bearings and to which power may be applied. 35 The lower end of the frame may be raised and lowered by some such apparatus as the tackle 13.

The driving-shaft 12 has fixed upon it a wheel or tumbler 14, preferably provided 40 with end cheeks or flanges 15. Mounted upon spokes 16 of this wheel between the flanges are polygonal faces 17, which may have the form particularly illustrated in Fig. 5 of the drawings and having separably attached to 45 them wearing-plates 18. A shaft 19 is journaled in the lower end of the frame and has fixed upon it a wheel or tumbler, here shown as formed of separated members 20, each of 50 which has a flange 21, lying in alinement with the flanges of the wheel 14. The spokes 22

of this lower wheel carry faces 23, corresponding to the faces 17, they having the form particularly illustrated in Fig. 3 and also being provided with removable wearing-plates 24. Both the plates 18 and 24 have 55 alternating projections 25 and depressions 26, forming transverse corrugations. Over the wheels operate a series of buckets 27 of a form best adapted to carry out the operations to which they are to be applied, said buckets 60 being pivotally connected at 28 and each having upon its inner face a contact-plate 29 of the form shown in Fig. 6. These contact-plates 29 have transverse corrugations for co-operation with those upon the wearing-plates 65 of the wheels. Between the wheels arranged along the upper edge of the frame are a suitable number of supporting-rolls 30, which are toothed or corrugated to engage the projections and depressions upon the contact- 70 plates of the buckets.

At the lower end of the frame adjacent to the wheel 20 is preferably mounted a shield 31 of inverted-V shape, which extends from a point adjacent to said wheel upward for a considerable distance along the frame. This prevents the material dropping from the upper run of buckets from being caught upon the lower end of the frame and carried into the 75 wheel, where it would tend to produce undue wear.

As apparatus of this class is usually operated there is much relative movement or slipping between the buckets and the supporting-wheels, which causes the coating surfaces to 80 wear quickly and shortens the life of the parts. It will be obvious that the engagement between the corrugated faces which we provide will compel the elements to move together, greatly reducing the wear, and what 85 occurs is received by readily removable plates, which may be replaced at comparatively slight expense whenever it becomes necessary. The toothed engagement between the buckets and rolls compels the latter to 90 move with the former at the same rate and avoids the danger of the rolls becoming stuck, and thus becoming stationary and wearing the buckets and becoming themselves worn 95 into flattened sections.

Having thus described our invention, we claim as new and desire to secure by Letters Patent—

1. In a dredge, the combination with a wheel 5 provided with a plurality of separable plates arranged about its periphery, of a bucket having a removable contact-plate coöperating with the wheel.
2. In a dredge, the combination with upper 10 and lower wheels, of a series of buckets movable over the wheels and having alternate

projections and depressions, and a supporting-roll situated between the wheels and having coöperating projections and depressions.

In testimony whereof we have signed our ¹⁵ names to this specification in the presence of two subscribing witnesses.

JAMES HENDERSON.
HARRY G. PEAKE.
